RAILWAY SIGNALING APPARATUS

Paul N. Martin, Penn Township, Allegheny County, Pa., assignor to The Union Switch & Signal Company, Swissvale, Pa., a corporation of Pennsylvania

Application August 31, 1938, Serial No. 227,807

11 Claims. (Cl. 246—130)

My invention relates to railway signaling apparatus, and is particularly well adapted for, but not limited thereto, governing highway crossing signals located at the intersection of a highway and a railway track.

An object of my invention is the provision of novel and improved directional signal control means wherein the shunting sensitivity of the control track circuits is improved so that improper signal operation will not be effected by momentary losses of train shunt in the control sections. Apparatus embodying my invention is particularly effective in assuring that light railway equipment, which may provide only a high resistance train shunt, will maintain directional control of traffic controlling signals.

Other features and advantages of my invention will appear as the specification progresses.

I shall describe several forms of apparatus embodying my invention, and shall then point out the novel features thereof in claims.

In the accompanying drawings, Fig. 1 is diagrammatic view showing novel and improved railway signaling apparatus embodying my invention when applied to controlling a highway crossing signal. In Fig. 1, "primary-secondary" relay combinations serve to govern the directional control means for the highway crossing signal S. Figs. 2, 3 and 4 are diagrammatic views showing modified forms of the apparatus of Fig. 1, and also embodying my invention. In Figs. 1, 2, 3 and 4, the "primary-secondary" relay combinations are so controlled that the primary relay is shifted to its pick-up circuit whenever a train is on the track section associated with that relay. Figs. 5, 6 and 7 are diagrammatic views showing further modified forms of the apparatus of Fig. 1 and also embodying my invention. In Figs. 5, 6 and 7, the relay combinations are so controlled that the relay on the receding side of the signal is not shifted to its pick-up circuit until the train passes the signal. Figs. 8 and 9 are each diagrammatic views showing still further modified forms of the apparatus of Fig. 1, and also embodying my invention. In Figs. 8 and 9, the relay combinations are so governed that the track relays for both sections are shifted to their pick-up circuits whenever a control section is entered by a train.

In directional signal control means hitherto proposed, the control sections are usually provided with the ordinary track circuits in accordance with the existing state of the art. In the ordinary track circuit, since the normal energy level effective at the track relay is considerably

above the pick-up value of the relay, the train shunt must be sufficiently effective to by-pass the increment above the release value of the relay. This requires not only a relatively low resistance train shunt, but also requires the shunt to be effective for an appreciable time interval since the relay flux requires an appreciable time to die down from the normal energy level to the release level.

Apparatus embodying my invention diminishes the possibility of improper operation of directional signal control means resulting from a momentary loss of train shunt or from an intermittent high resistance train shunt in the control section. Effective maintenance of directional control is made possible by reducing the normal energy level for the track relay below the pick-up value, both by decreasing the effective turns and by inserting resistance in series with the operating winding of the relay after it picks up, thereby enabling a higher resistance train shunt to release the relay. The decrease in the number of turns and the addition of resistance in series with the winding of the track relay not only aid to decrease the energy level but also cause a more rapid flux decay on account of a decrease in inductance to resistance ratio, thus decreasing the release time of the relay. It follows that when a track relay picks up on a loss of shunt within a control section, the relay is at once transferred to its holding circuit, whereby its energization will be immediately reduced so that it will be more likely to release again before the directional control means which it governs has had an opportunity to become affected.

Referring to Fig. 1, the reference characters I and Ia designate the track rails of a stretch of railway track over which trains move in both directions, and which is intersected at grade by a highway H.

The reference character S designates a traffic controlling signal, here shown as a highway crossing signal. Signal S is preferably located adjacent the intersection and may be any one of the usual types, but as here shown is an audible signal in the form of an electric bell.

The track rails I and Ia are divided by means of the usual insulated rail joints 2 to form control sections D—E and E—F. Sections D—E and E—F preferably extend in opposite directions from the intersection and, preferably, the sections are of such length suitable to provide an adequate warning period to highway users of the approach of a train to the intersection. Each section is provided with a track circuit compris-

ing a source of current, such as track battery 3, connected across the track rails at one end of the section, and the operating winding of the primary relay of a primary-secondary relay combination connected across the track rails at the other end. The track circuit for section D—E includes the operating winding of relay TR1 which is illustrated in Fig. 1 in the form of two coils 6 and 8 corresponding to the two coils of the usual track relay, and the track circuit for section E—F includes the operating winding of relay TR2, shown as the two coils 6a and 8a.

As shown in Fig. 1, the upper terminal of coil 6 of relay TR1 is connected with the rail 1 over a wire 6n and the upper terminal of coil 8 of relay TR1 is connected with the rail 1a over a wire 8n. The two lower terminals of coils 6 and 8 of relay TR1 are at times connected together over a circuit serially including front contact 82 of a relay Q1, to be referred to later, and back contact 39 of an interlocking relay IR, also to be referred to later. A resistor 9 is connected between an intermediate terminal of coil 6 of relay TR1 and the lower terminal of coil 8 of relay TR1 at such times as back contact 86 of relay Q1 is closed. In like manner, the upper terminal of coil 6a of relay TR2 is connected with rail 1 over wire 6r and the upper terminal of coil 8a of relay TR2 is connected with rail 1a over wire 82. The two lower terminals of coils 6a and 8a are at times connected together over a circuit serially including front contact 83 of a relay Q2, to be referred to later, and back contact 41 of interlocking relay IR. A resistor 9a is connected between an intermediate terminal of coil 6a of relay TR2 and the lower terminal of coil 8a of relay TR2 at such times as back contact 87 of relay Q2 is closed. It can be seen that the pick-up circuit for relay TR1 or TR2 includes the entire operating winding of the relay and excludes the resistor 9 or 9a, whereas the holding circuit includes only a portion of the operating winding of the relay and includes resistor 9 or 9a. It follows that, since the pick-up circuit for relay TR1 or TR2 includes the whole operating winding of the relay, the relay when connected across the track rails in its pick-up circuit is maintained at a high energy level, usually at that energy level required to pick up the relay. However, when the relay is connected across the track rails in its holding circuit, the energy level of the relay is decreased from the level established by the pick-up circuit, with the energy level of the relay in its holding circuit usually being only sufficiently above the release value of the relay to assure reliable operation under the various ballast conditions.

The relays Q1 and Q2 are associated respectively with relays TR1 and TR2, and are preferably provided with slow releasing characteristics. Relay Q1 is energized over a simple circuit including back contact 31 of relay TR1, and so serves as an auxiliary or secondary relay for relay TR1. Relay Q2 is energized over a simple circuit including back contact 37 of relay TR2, and so serves as an auxiliary or secondary relay for relay TR2.

The interlocking signal operating relay IR, referred to previously, may be of any suitable type, such as, for example, the relay covered by United States Letters Patent No. 1,799,629, granted to W. K. Lockhart and T. J. O'Meara on April 7, 1931. This type of relay is well known and is characterized by the fact that when the left-hand winding W1 is deenergized, the downward movement of the armature associated therewith

operates a mechanical locking device which keeps the armature associated with the right-hand winding W2 "locked up" in approximately its mid position, so that a subsequent deenergization of winding W2 while winding W1 is still deenergized cannot close back contact 40. Similarly, if the right-hand winding W2 is first to be energized, then back contact 38 is prevented from closing when the left-hand winding W1 becomes deenergized during the interval that winding W2 is still deenergized. Winding W1 is provided with back contact 39 which is so arranged as to be closed when winding W1 is in its full released or its "locked up" position. Back contact 41 of winding W2 is similarly arranged to close in the "locked up" and full released positions of winding W2. Winding W1 is energized over a circuit passing from terminal B of a suitable source of current, such as a battery not shown, through front contact 4 of relay TR1, back contact 88 of relay Q1 and the winding W1 of relay IR to terminal C of the source of current. Winding W2 is energized over a circuit passing from terminal B through front contact 5 of relay TR2, back contact 88 of relay Q2 and the winding W2 of relay IR to terminal C. The windings W1 and W2 preferably are provided with slow pick-up characteristics.

Signal S is provided with an energizing circuit passing from terminal B through back contact 38 or back contact 40 of relay IR, and the winding of signal S to terminal C of the source of current. It can be seen, therefore, that back contact 38 of winding W1 and back contact 40 of winding W2 function as signal control contacts, winding W1 serving as an operating relay for governing signal S for eastbound traffic, and winding W2 serving as an operating relay for governing signal S for westbound traffic. The interlocking feature of relay IR, as will appear more clearly later, serves as directional means for preventing winding W1 from serving as an operating relay for westbound traffic, and prevents winding W2 from functioning as an operating relay for eastbound traffic.

I shall now explain the manner in which the apparatus of Fig. 1 operates. I shall first assume that the sections D—E and E—F are unoccupied so that the apparatus is in its normal condition, that is, the condition illustrated in Fig. 1. In this condition of the apparatus, relays TR1, TR2 and windings W1 and W2 of relay IR are energized, and relays Q1, Q2 and signal S are deenergized. It should be noted that when relays Q1 and Q2 are deenergized, relays TR1 and TR2 are connected across the track rails in their holding circuits whereby the energy levels of the relays are reduced nearly to the release value of the relays.

I shall now assume that an eastbound train, that is, a train operating from left to right in Fig. 1, enters section D—E. When this happens, relay TR1 is shunted and quickly releases, thereby opening front contact 4 to open the energizing circuit for winding W1 so that winding W1 releases, and closing back contact 31 to complete the energizing circuit for relay Q1 so that relay Q1 picks up. The release of winding W1 closes back contact 38 to complete the energizing circuit for signal S and thereby sets the signal into operation, and also closes back contact 39 to prepare the pick-up circuit for relay TR1. The picking up of relay Q1 opens back contact 86, thereby opening the circuit connecting resistor 9 across the intermediate terminal of coil 6 and the lower

terminal of coil 8 of relay TR1, and closes front contact 82 to complete the pick-up circuit for relay TR1.

If the resistance of the train shunt varies intermittently as the train passes through section D—E, the primary relay TR1 may pick up and release, following the variations of the train shunt resistance, but the operating relay W1 will not pick up and so open the signal control contact 38. In the case of the ordinary track relay controlling an operating relay, the operating relay usually will pick up and release following the fluctuation of the track relay, and so momentarily open the signal control contact thereby permitting improper operation of the signal device. With the apparatus of Fig. 1, however, after a train enters the section and causes relay TR1 and winding W1 to release and relay Q1 to pick up, if a high resistance train shunt occurs so that the track relay TR1 picks up over its pick-up circuit, the auxiliary relay Q1 will release at the end of its slow release period, opening front contact 82 and thereby opening the pick-up circuit for relay TR1, and closing back contact 88 thereby completing the energizing circuit for winding W1, and back contact 86, thereby completing the holding circuit for relay TR1 and so reducing its energization. This reduced energization will, under ordinary variations of train shunt, be sufficient to release the track relay. Since winding W1 does not become energized unless relay TR1 is picked up and relay Q1 is released, and since relay TR1 releases when relay Q1 releases to complete the holding circuit for relay TR1, the energizing circuit for winding W1 is but momentarily completed so that winding W1 does not pick up at the end of its slow pick-up period to open back contact 38. Should the intermittent train shunt persist for a prolonged time interval, there would result only a "pumping" action of the relays TR1 and Q1 without operation of the signal control contact 38 of winding W1. It follows that winding W1 when combined with track relay TR1 and repeater relay Q1 in the manner set forth hereinbefore is effective to avoid false operation of traffic controlling devices due to an intermittent train shunt of high resistance in section D—E.

When the train enters section E—F, relay TR2 quickly releases, thereby opening front contact 5 to open the energizing circuit for winding W2 so that winding W2 releases its armature to its "locked up" position, and closing back contact 37 to complete the energizing circuit for relay Q2 so that relay Q2 picks up. The release of winding W2 closes back contact 41 to prepare the pick-up circuit for relay TR2, but back contact 40 is held open by virtue of the interlocking feature of relay IR. The picking up of relay Q2 opens back contact 87 thereby opening the holding circuit for relay TR1, and closes front contact 83 to complete the pick-up circuit for relay TR2.

In the event that intermittent variations of train shunt occur in sections D—E and E—F, relays TR1 and TR2 may pick up and release but the operating relay W1 will not pick up and so interrupt the signal operation, nor will winding W2 pick up to affect the directional set-up for the signal operation. If relay TR1 picks up due to high resistance shunt, the relay is transferred to its holding circuit and releases prior to winding W1 picking up, as explained hereinbefore. If relay TR2 picks up due to high resistance shunt, relay Q2 releases at the end of its slow release period to connect relay TR2 across the track rails

in its holding circuit, thereby reducing the energization of relay TR2 with the result that relay TR2 releases, and the release of relay TR2 opens the circuit for winding W2 so that the directional control for signal S is not altered.

When the train vacates section D—E, relay TR1 picks up, relay Q1 releases to connect relay TR1 across the track rails in its holding circuit, and winding W1 picks up to terminate the operation of signal S. With the train entirely within section E—F, an intermittent variation in train shunt might result in relay TR2 picking up and releasing, but winding W2 does not pick up and so does not affect the directional control for signal S, as explained hereinbefore.

When the train vacates section E—F, relay TR2 picks up, relay Q2 releases, and winding W2 picks up so that the apparatus is restored to its normal condition.

The operation of the apparatus of Fig. 1 for a westbound train is similar to the operation just described for an eastbound train, and it is believed that the latter operation will be apparent from the foregoing description together with an inspection of Fig. 1 without further detailed description.

Referring now to Fig. 2, a modification of the apparatus of Fig. 1 is shown wherein a single normally deenergized secondary relay Q cooperates with relay IR to control the pick-up circuits for relays TR1 and TR2, the slow release secondary relay Q being energized over a simple circuit including back contact 64 of relay TR1 or back contact 65 of relay TR2. The slow release period for relay Q, as will be explained hereinafter, is preferably shorter than the slow pick-up period of winding W1 or W2 of relay IR. Winding W1 of relay IR is now energized over a simple circuit easily traced including front contact 62 of relay TR1. Winding W2 of relay IR is now energized over a simple circuit including front contact 63 of relay TR2. The operating circuit for signal S is the same as traced in connection with the apparatus of Fig. 1.

The track circuit for section D—E of Fig. 2 is similar to the circuit described for section D—E of Fig. 1, except that resistor 9 is now permanently connected between the intermediate terminal of coil 6 and the lower terminal of coil 8 of relay TR1, and the two lower terminals of coils 6 and 8 of relay TR1 are at times connected together over a circuit serially including front contact 42 of relay Q and back contact 39 of relay IR. Likewise, the track circuit for section E—F of Fig. 2 is similar to the circuit described for section E—F of Fig. 1, except that resistor 9a is now permanently connected between the intermediate terminal of coil 6a and the lower terminal of coil 8a of relay TR2, and the two lower terminals of coils 6a and 8a of relay TR2 are at times connected together over a circuit serially including front contact 43 of relay Q and back contact 41 of relay IR. It can be seen that relay TR1 or TR2 is provided with two circuits, a pick-up circuit for the relay including the full operating winding of the relay and excluding resistor 9 or 9a, and a holding circuit for the relay including only a portion of the operating winding of the relay and including resistor 9 or 9a. It follows that when relay TR1 or TR2 is connected across the track rails in its holding circuit, the number of effective coil turns, and consequently, the energy level, of the relay is greatly reduced. It will be understood, of course, that my invention is not restricted to the one form of primary-

secondary relay combination chosen to serve as an illustration, but that the scope of my invention embraces any of the usual primary-secondary relay combinations wherein the primary relay is provided with a holding circuit and a pick-up circuit including a contact of the secondary relay.

The apparatus of Fig. 2 is in its normal condition, as shown in Fig. 2, when no train occupies track section D—E or E—F. In this condition of the apparatus, the track relays TR₁ and TR₂ are energized, windings W₁ and W₂ of relay IR are energized, and relay Q and signal S are de-energized.

- 15 When an eastbound train enters track section D—E, relay TR₁ releases, thereby closing back contact 64 and opening front contact 62. The opening of front contact 62 of relay TR₁ opens the energizing circuit for winding W₁, with the result that winding W₁ releases to close back contacts 38 and 39, the closing of back contact 38 completing the operating circuit for signal S with the result that signal S starts operating, and the closing of back contact 39 preparing the pick-up circuit for relay TR₂. The closing of back contact 64 of relay TR₁ completes the energizing circuit for relay Q with the result that relay Q becomes energized and picks up to close front contact 42, thereby connecting relay TR₁ across the track rails over its pick-up circuit, and front contact 43 thereby preparing the pick-up circuit for relay TR₂.

When the train enters track section E—F, relay TR₂ releases to close back contact 65 which completes a second circuit for relay Q, and to open front contact 63. The opening of front contact 63 of relay TR₂ opens the energizing circuit for winding W₂, with the result that winding W₂ releases to close back contact 41, thereby connecting relay TR₂ across the track rails in its pick-up circuit, and to release back contact 46 to its "locked up" position.

When the train vacates section D—E, relay TR₁ picks up to open back contact 64, thereby opening the circuit for relay Q governed by that contact, and to close front contact 62, thereby completing the energizing circuit for winding W₁. Winding W₁ picks up, back contact 39 opening to connect relay TR₁ across the track rails over its holding circuit, and back contact 38 opening to open the circuit for, and terminate the operation of, signal S.

When the train vacates section E—F, relay TR₂ and winding W₂ pick up and relay Q releases. Relay TR₂ is now connected across the track rails over its holding circuit, and the apparatus is restored to its normal condition.

Directional control of signal S is maintained by virtue of the slow pick-up characteristics of the windings of the interlocking relay and the relatively quicker release characteristics of relay Q. When a momentary loss of train shunt occurs while the train is entirely within track section D—E, the track relay TR₁ might pick up, thereby opening back contact 64 to deenergize relay Q, and closing front contact 62 to energize winding W₁. Relay Q releases, however, and thereby opens the pick-up circuit for relay TR₁ with the result that the energy level in relay TR₁ is reduced so that the relay will be shunted quickly upon a restoration of a moderately low resistance train shunt across the track rails. Relay TR₁ thus will release again prior to the completion of the slow pick-up interval of winding W₁.

with the result that the directional control of signal S is not affected.

Similarly, a loss of train shunt in track section E—F, while the train is occupying both track sections D—E and E—F, does not result in loss of directional control. Furthermore, a loss of shunt in section D—E, while the train occupies both sections D—E and E—F, does not result in loss of directional control, inasmuch as the interlocking mechanism of relay IR is such that once the armature controlled by winding W₂ is released to its mid or locked position, it must be energized again before it can drop to its full released position. It is obvious that the slow pick-up characteristics of winding W₂ will operate in a similar manner when, with the train entirely on track section E—F, relay TR₂ becomes deenergized due to a loss of train shunt.

The operation of the apparatus of Fig. 2 for a westbound train is similar to that just described for an eastbound train, as will become readily apparent from an inspection of Fig. 2.

Referring to Fig. 3, a modification of the apparatus of Fig. 1 is shown wherein directional control of the signals is effected by stick relays. The track circuit for section D—E of Fig. 3 is similar to the circuit for section D—E in Fig. 2 except that the lower terminals of coils 6 and 8 of relay TR₁ are at times connected together over a circuit including back contact 7 of a relay TP₁. The track circuit for section E—F of Fig. 3 is likewise similar to the track circuit for section E—F of Fig. 2 except that the lower terminals of coils 6a and 8a of relay TR₂ are at times connected together over a circuit including back contact 10 of a relay TP₂.

Relay TP₁ is energized over a simple circuit including front contact 4 of relay TR₁, and hence serves as a repeater or secondary relay for relay TR₁. Relay TP₂ is energized over a simple circuit including front contact 5 of relay TR₂ and hence serves as a repeater or secondary relay for relay TR₂. Relays TP₁ and TP₂ are preferably provided with slow pick-up characteristics.

The directional stick relays SR₁ and SR₂ are preferably provided with a release period longer than the pick-up period for the repeater relays TP₁ and TP₂. The pick-up circuit for relay SR₁ passes from terminal B through back contact 11 of relay TR₁, back contact 12 of relay SR₂ and the winding of relay SR₁ to terminal C. The stick circuit for relay SR₁ passes from terminal B through back contact 13 of relay TR₂, front contact 14 of relay SR₁ and the winding of relay SR₁ to terminal C. Similarly, the pick-up circuit for relay SR₂ passes from terminal B through back contact 13 of relay TR₂, back contact 15 of relay SR₁ and the winding of relay SR₂ to terminal C. The stick circuit for relay SR₂ passes from terminal B through back contact 16 of relay TR₁, front contact 16 of relay SR₂ and winding of relay SR₂ to terminal C. It is to be noted that relays SR₁ and SR₂ are each provided with a so-called "snubbing circuit," that is, a short circuit path across the winding of the relay whereby the magnetic flux created thereby is maintained for a relatively long period so that an additional delay is introduced for the release period of the relay. The snubbing circuit for relay SR₁ may be traced from the left terminal of relay SR₁ through front contact 21 of relay TR₁, front contact 22 of relay TR₂ and front contact 14 of relay SR₁ to the right terminal of relay SR₁. The snubbing

circuit for relay SR2 may be traced from the right terminal of relay SR2 through front contact 23 of relay TR2, front contact 24 of relay TR1 and front contact 16 of relay SR2 to the 5 left terminal of relay SR2.

A first operating circuit for signal S passes from terminal B through back contact 17 of relay SR2, back contact 18 of relay TP1 and the winding of signal S to terminal C. A second operating circuit for signal S passes from terminal B through back contact 19 of relay SR1, back contact 20 of relay TP2 and the winding of signal S to terminal C.

The apparatus is in its normal condition, as 15 shown in Fig. 3, when track sections D-E and E-F are unoccupied. In this condition, track relays TR1 and TR2 are held energized by their holding circuits, relays TP1 and TP2 are energized, stick relays SR1 and SR2 are deenergized, and signal S is deenergized.

When an eastbound train enters track section D-E, track relay TR1 is shunted and releases. When this happens, back contact 11 of relay TR1 closes and front contacts 4, 21 and 24 open. 25 The opening of front contact 4 opens the energizing circuit for relay TP1. Relay TP1 is deenergized and releases to close back contact 18, thereby completing the first operating circuit for signal S so that signal S starts operating, and to 30 close back contact 7, thereby connecting relay TR1 across the track rails over its pick-up circuit. The opening of front contacts 21 and 24 of relay TR1 opens, respectively, the snubbing circuits for relay SR1 and relay SR2. The closing 35 of back contact 11 of relay TR1 completes the pick-up circuit for relay SR1 with the result that relay SR1 picks up to open the back contacts 19 and 15, which are interposed in the second operating circuit for signal S and the pick-up 40 circuit of the opposing stick relay SR2, respectively, and to close front contact 14 to prepare the stick circuit for relay SR1.

If the resistance of the train shunt in section D-E varies, relays TR1 and TP1 may pick up 45 following the variation in train shunt, but the directional stick relay SR1 is not affected. For a momentary high resistance train shunt in section D-E, relay TR1 may pick up over its pick-up circuit. The picking up of relay TR1 may in 50 turn pick up relay TP1 and thus interrupt the operation of signal S momentarily at back contact 18, but when relay TP1 picks up, relay TR1 is shifted to its holding circuit so that relay TR1 is ordinarily released prior to relay SR1 releasing at the termination of its slow release period. 55 It can be seen that although the operation of signal S may be momentarily interrupted, the directional stick relay SR1 is not affected by the loss of train shunt.

When the train enters track section E-F on 60 its way past the intersection, relay TR2 quickly releases to open front contacts 5, 22 and 23, and to close back contact 13. The closing of back contact 13 of relay TR2 completes the stick circuit for relay SR1, as previously traced, and the opening of front contact 5 of relay TR2 opens the energizing circuit for relay TP2 with the result that relay TP2 releases to close back contact 10 and thereby connect relay TR2 across 65 the track rails over its pick-up circuit.

It should be pointed out that a momentary loss of train shunt when a train is occupying both track sections D-E and E-F does not result in loss of directional control. If the train shunt is 70 momentarily lost in track section D-E, the ap-

paratus maintains the directional stick relay SR1 picked up until the shunt is restored, as mentioned hereinbefore. A momentary loss of train shunt in track section E-F has no effect upon the operation of the signal or of the directional stick relay, since the signal and the directional stick relay are each energized over circuits controlled by track section D-E. A momentary loss of train shunt in both track sections D-E and E-F does not result in loss of directional control even though the train shunt be restored first to track section E-F since relay SR1 remains in its picked-up condition due to the slow releasing characteristics until either track relay TR1 or TR2 again becomes deenergized. If the train shunt is restored to section E-F prior to a restoration in track section D-E, relay TR2 becomes deenergized to reestablish the stick circuit for relay SR1. If the train shunt is restored to track section D-E prior to a restoration in track section E-F, relay TR1 becomes deenergized to reestablish the pick-up circuit for relay SR1. As long as relay SR1 remains picked up, the first operating circuit for signal S may be completed and the energizing circuit for the directional stick relay SR2 cannot be completed.

When the train vacates section D-E, relays TR1 and TP1 become reenergized. Relay TP1 picks up at the end of its slow pick-up period 30 to open the first operating circuit for signal S so that signal S stops operating, and to connect relay TR1 across track rails 1 and 1a over its holding circuit. The pick-up circuit for relay SR1 is opened when relay TR1 picks up, but 35 relay SR1 remains energized over its stick circuit including back contact 13 of relay TR2. While the train is entirely within track section E-F, a momentary loss of train shunt and resultant reenergization of relay TR2 does not result in false operation of the signal or loss of directional control. Relay TR2 may pick up but when relay TP2 picks up, relay TR2 is connected in its holding circuit and so releases, prior to the expiration of the slow release period of 40 the direction stick relay SR1, to reestablish the stick circuit for relay SR1.

When the train vacates track section E-F, relay TR2 picks up to open the stick circuit for relay SR1 and to complete the energizing circuit for relay TP2. Relay TP2 picks up at the end of its slow pick-up period to connect relay TR2 across the track rails in its holding circuit, and relay SR1 releases at the end of its slow release period. The apparatus is now in its normal 55 condition.

The operation of the apparatus of Fig. 3 for a westbound train is similar to that just described for an eastbound train, and it is believed that the latter operation will be apparent from the foregoing description together with an inspection of Fig. 3 without further detailed description.

Referring now to Fig. 4, a modification of the apparatus of Fig. 1 is shown wherein the operation of signal S is governed by an operating relay TP3. The track circuit for section D-E of Fig. 4 is similar to the circuit described in connection with Fig. 3, except that the two lower terminals of coils 6 and 8 of relay TR1 are at times connected together over a circuit including front contact 82 of relay Q1. Likewise, the track circuit for track section E-F of Fig. 4 is similar to the circuit described for section E-F in connection with Fig. 3 except that the two lower terminals 70 of coils 6 and 8 of relay TR2 are at times connected together over a circuit including front contact 82 of relay Q2. The apparatus of Fig. 4 is similar to the apparatus of Fig. 3 except that the two lower terminals 75 of coils 6 and 8 of relay TR1 and the two lower terminals of coils 6 and 8 of relay TR2 are connected together over a circuit including front contact 82 of relay Q1 and front contact 82 of relay Q2.

minals of coils 6a and 8a of relay TR2 are at times connected together over a circuit including front contact 83 of relay Q2.

- 5 Directional control of traffic controlling signal S is established through the medium of the slow releasing stick relays SR1 and SR2. The pick-up circuit for relay SR1 passes from terminal B through front contact 84 of relay Q1, back contact 12 of relay SR2 and the winding of relay 10 SR1 to terminal C. The stick circuit for relay SR1 passes from terminal B through front contact 85 of relay Q2, front contact 14 of relay SR1 and the winding of relay SR1 to terminal C. In like manner, relay SR2 is provided with a pick-up circuit which may be traced from terminal B through front contact 85 of relay Q2, back contact 15 of relay SR1 and the winding of relay SR2 to terminal C, and with a stick circuit which may be traced from terminal B through front contact 84 of relay Q1, front contact 16 of relay SR2 and the winding of relay SR2 to terminal C.

- Signal S is provided with an energizing circuit passing from terminal B through back contact 33 of operating relay TP3, and the winding 25 of signal S to terminal C. The operating relay TP3 is preferably provided with slow pick-up characteristics, and is normally energized over a first circuit passing from terminal B through front contact 54 of relay TR1, back contact 80 30 of relay Q1, back contact 31 of relay Q2, front contact 55 of relay TR2 and the winding of relay TP3 to terminal C. At times, however, relay TP3 is energized over a second circuit passing from terminal B through front contact 54 of relay TR1, back contact 80 35 of relay Q1, front contact 57 of relay SR1, back contact 32 of relay TR2 and the winding of relay TP3 to terminal C; and at other times is energized over a third circuit passing from terminal B through back contact 31 40 of relay TR1, front contact 56 of relay SR2, back contact 31 of relay Q2, front contact 55 of relay TR2 and the winding of relay TP3 to terminal C.

When sections D—E and E—F are unoccupied, the apparatus is in its normal condition as shown 45 in Fig. 4. In this condition of the apparatus, relays TR1 and TR2 are held energized over their holding circuits, relay TP3 is energized, the relays Q1, Q2, SR1 and SR2 are deenergized, and signal S is deenergized.

- 50 When an eastbound train enters section D—E, relay TR1 quickly releases, thereby opening front contact 54 to open the first circuit for relay TP3 so that relay TP3 releases, and also closing back contact 31 to complete the energizing circuit for relay Q1, whereupon relay Q1 picks up. The release of relay TP3 closes back contact 33 to complete the energizing circuit for signal S, with the result that signal S starts operating. The picking up of relay Q1 closes front contact 82, 55 60 thereby connecting together the lower terminals of coils 6 and 8 of relay TR1 so that relay TR1 is connected across the track rails over its pick-up circuit, and closing front contact 84 to complete the pick-up circuit for relay SR1. Relay SR1 picks up, opening back contact 15 to open the pick-up circuit for relay SR2, and closing front contact 14 to prepare the stick circuit for relay SR1, and closing front contact 57 to prepare the second circuit for relay TP3.

- 70 In the event that the resistance of the train shunt varies intermittently as the train passes through section D—E, relay TR1 may pick up and release, but the operating relay TP3 and the directional stick relay SR1 will not pick up to 75 interrupt, respectively, the operation of signal

S and the directional control for signal S. If relay TR1 picks up over its pick-up circuit due to a momentarily high resistance train shunt, relay Q1 will release at the end of its slow release period to open back contact 82 and thereby transfer relay TR1 to its holding circuit, whereby the energization of relay TR1 is reduced so that relay TR1 releases. The release of relay TR1 de-energizes relay Q1 with the result that the energizing circuit for relay SR1 is again completed prior to that relay releasing at the end of its slow release period, and the energizing circuit for relay TP3 is opened prior to that relay picking up at the end of its slow pick-up period. It follows that relay TP3 is effective to avoid false operation of signal S due to an intermittent high resistance train shunt in section D—E.

When the train enters section E—F, relay TR2 quickly releases, thereby opening front contact 55 to open the first circuit for relay TP3, closing back contact 32 to prepare the second circuit for relay TP3, and closing back contact 37 to complete the energizing circuit for relay Q2. Relay Q2 picks up to close front contact 33 and thereby connect relay TR2 in its pick-up circuit, and to close front contact 85 to complete the stick circuit for relay SR1.

It should be noted that intermittent high resistance train shunts, occurring while a train occupies sections D—E and E—F, will not result in false operation of signal S or of the directional control of signal S. If relay TR1 picks up due to a high resistance train shunt in section D—E, relay Q1 will release and transfer relay TR1 to its holding circuit whereby the energy level of the relay is reduced so that relay TR1 releases prior to relay TP3 picking up, and also prior to relay SR1 releasing. If relay TR2 picks up due to a high resistance train shunt in section E—F, relay Q2 releases to transfer TR2 to its holding circuit and thereby reduce the energy level of the relay so that relay TR2 releases prior to relay SR1 releasing and opening front contact 14 to open the stick circuit for relay SR1. It follows that the operation of signal S and the control of the directional stick relay SR1 is not affected by variations in resistance of the train shunt in sections D—E and E—F.

When the train vacates section D—E, relay TR1 picks up to open front contact 31 and thereby open the energizing circuit for relay Q1, and to close front contact 54 to prepare the second circuit for relay TP3. When relay Q1 releases at the end of its slow release period, back contact 80 closes to complete the previously traced second circuit for relay TP3 so that relay TP3 becomes energized and picks up at the end of its slow pick-up period to open back contact 33 and terminate the operation of signal S. The release of relay Q1 also opens front contact 82 with the result that relay TR1 is now connected in its holding circuit, and opens front contact 84 to open the pick-up circuit for relay SR1.

When the train occupies section E—F, a momentary high resistance train shunt, resulting in relay TR2 picking up, will not effect improper signal operation. Relay TR2 may pick up, but when relay Q2 releases, relay TR2 is connected in its holding circuit so that the energy level of the relay is greatly reduced with the result that relay TR2 will release prior to relay SR1 releasing at the end of its slow release period to open the stick circuit for that relay. The release of relay TR2 reenergizes relay Q2 which then

completes the stick circuit for relay SR1, thereby maintaining the directional control for signal S.

When the train vacates section E—F, relay TR2 picks up and relay Q2 releases, the releasing of relay Q2 connecting relay TR2 in its holding circuit and opening the stick circuit for relay SR1 so that relay SR1 releases. The apparatus is now restored to its normal condition.

The operation of the apparatus of Fig. 4 for a westbound train is similar to that just described for an eastbound train, as will become readily apparent from an inspection of Fig. 4.

Referring now to Fig. 5, the operating relay TP3 cooperates with the stick relays SR1 and SR2 to provide directional control of the release sensitivity of the track relays. That is to say, the track relay on the receding side of the intersection is maintained in its sensitive, or holding, circuit until the train has cleared the intersection and the operation of the signal is terminated.

In Fig. 5, the lower terminals of the coils 6 and 8 of relay TR1 are at times connected together over a first circuit serially including front contact 28 of relay TP3 and front contact 27 of relay SR2, and at other times over a second circuit serially including back contact 25 of relay TP3 and back contact 67 of relay SR2. The lower terminals of coils 6a and 8a of relay TR2 are at times connected together over a first circuit serially including front contact 30 of relay TP3 and front contact 29 of relay SR1, and at other times connected together over a second circuit serially including back contact 26 of relay TP3 and back contact 66 of relay SR1.

The normal energizing circuit for relay TP3 passes from terminal B of the source of current through front contact 54 of relay TR1, front contact 55 of relay TR2 and the winding of relay TP3 to the other terminal C of the current source.

A second energizing circuit for relay TP3 passes from terminal B through back contact 31 of relay TR1, front contact 56 of relay SR2, front contact 57 of relay TR2 and the winding of relay TP3 to terminal C. A third energizing circuit for relay TP3 passes from terminal B through front contact 54 of relay TR1, front contact 57 of relay SR1, back contact 32 of relay TR2 and the winding of relay TP3 to terminal C. The operating circuit for signal S passes from terminal B through back contact 33 of relay TP3 and the winding of signal S to terminal C. The pick-up and stick circuits for relays SR1 and SR2 are the same as traced for Fig. 3.

The apparatus is in its normal condition, that is, the condition illustrated in Fig. 5, when track sections D—E and E—F are unoccupied. Relays TR1 and TR2 are held energized over their respective holding circuits, and relay TP3 is held energized over its normal energizing circuit. Relays SR1 and SR2 are deenergized, and the operating circuit for signal S is open at back contact 33 of relay TP3 so that the signal does not operate.

When an eastbound train enters track section D—E, relay TR1 is shunted and releases to open front contact 54, thereby opening the normal energizing circuit for relay TP3 with the result that relay TP3 releases. Back contact 33 of relay TP3 now closes to complete the operating circuit for signal S, and signal S starts operating. The release of relay TP3 also closes back contact 25 to complete the second circuit in the pick-up circuit for relay TR1 and thereby connects relay TR1 across the track rails over its pick-up circuit. Back contact 11 of relay TR1 also closes to complete the pick-up circuit for relay SR1

so that relay SR1 picks up to open back contacts 15 and 66, and to close front contacts 14, 29 and 57. The opening of back contacts 15 and 66 of relay SR1 open, respectively, the pick-up circuit for relay SR2 and the second branch path in the pick-up circuit for relay TR2. The closing of front contact 14 prepares the stick circuit for relay SR1, the closing of front contact 29 prepares the second circuit connecting the lower terminals of coils 6a and 8a of relay TR2, and the closing of front contact 57 prepares the third energizing circuit for relay TP3.

When the train enters track section E—F, relay TR2 is shunted and releases to open front contact 55 and to close back contacts 13 and 32. The closing of back contact 13 completes the stick circuit for relay SR1, and the closing of back contact 32 of relay TR2 prepares the third circuit for relay TP3.

When the train vacates section D—E, relay TR1 picks up to close front contact 54 and to open back contacts 11 and 31. The opening of back contact 11 opens the pick-up circuit for relay SR1, but that relay is held energized over its stick circuit. The closing of front contact 54 of relay TR1 completes the third energizing circuit for relay TP3 whereby relay TP3 picks up to open back contacts 25, 26 and 33 and to close front contacts 28 and 30. The opening of back contact 33 opens the energizing circuit for signal S whereby signal S terminates its operation, and the opening of back contact 25 opens the second circuit in the pick-up circuit for relay TR1 so that relay TR1 is connected across the track rails in its holding circuit. The closing of front contact 30 completes the first circuit in the pick-up circuit for relay TR2 so that the relay TR2 is now connected across the track rails in its pick-up circuit.

When the train vacates section E—F, relay TR2 picks up to close front contact 55 and thereby complete the normal circuit for relay TP3, to open back contact 32 and open the third energizing circuit for relay TP3, and to open back contact 13 to open the stick circuit for relay SR1. Relay SR1 releases at the end of its slow release period and opens front contact 29 to open the first circuit in the pick-up circuit for relay TR2, whereby relay TR2 is connected across the track rails in its holding circuit.

The operation of the apparatus of Fig. 5 for a westbound train is similar to the operation just described for an eastbound train, as will become readily apparent from an inspection of Fig. 5.

The directional control of signal S and the operation of the signal is maintained by the apparatus of Fig. 5 by virtue of the slow acting characteristics of the stick and the operating relays, which relays are provided with the same characteristics as were mentioned in connection with Fig. 4. Since the utility of these slow acting features of the relays was described in detail in connection with the operation of the apparatus of Fig. 4, it is believed, therefore that the functioning of the slow acting characteristics of the relay will be readily apparent from the foregoing description without further detailed explanation. It should be pointed out, however, that since the pick-up circuits for relays TR1 and TR2 are controlled by relay TP3 cooperating with directional stick relays SR1 and SR2, directional control of the release sensitivity of the track relays is obtained. That is to say, when a train approaching the highway enters

section D—E or E—F, the relay associated with that section is released and is shifted to its pick-up circuit. Then, when the train recedes from the intersection through the other section, the relay associated with the other section is released. However, this latter relay is not shifted to its pick-up circuit until the train vacates the section on the approach side of the intersection. It follows that the relay for the track section on the receding side of the intersection is held in its sensitive condition until the train clears the intersection and the operation of the signal is terminated.

In Fig. 6, a modification of the apparatus of Fig. 1 is shown wherein the operating relay TP3 and the stick relays SR1 and SR2 cooperate with a slow releasing relay Q, which is preferably provided with a release period substantially shorter than the release period of relay SR1 or SR2, to govern the release sensitivity of the track relays. In Fig. 6, the track relay on the approach side of the intersection is shifted to its pick-up circuit when the train enters the approach section, the track relay on the receding side of the intersection is shifted to its pick-up circuit when the train vacates the section on the approach side of the intersection, and both track relays are held in their pick-up circuit until the train vacates the section on the receding side of the intersection.

Referring now to Fig. 6, the slow releasing auxiliary relay Q is energized over a simple circuit including back contact 64 of relay TR1 or back contact 65 of relay TR2. Relay TR1 is now connected in its pick-up circuit when the lower terminals of coils 6 and 8 of relay TR1 are connected together over a first circuit serially including front contact 28 of relay TP3 and front contact 27 of relay SR2, or over a second circuit serially including front contact 42 of relay Q and back contact 67 of relay SR2. Relay TR2 is now connected in its pick-up circuit when the lower terminals of coils 6a and 8a of relay TR2 are connected together over a first circuit serially including front contact 30 of relay TP3 and front contact 29 of relay SR1, or over a second circuit serially including front contact 43 of relay Q and back contact 66 of relay SR1.

The energizing circuits for relay TP3 and signal S are the same as were traced for Fig. 5. The pick-up circuit for relays SR1 and SR2 are the same as were traced in detail in connection with Fig. 3. The stick circuit for relay SR1 now passes from terminal B through front contact 36 of relay Q, front contact 14 of relay SR1 and the winding of relay SR1 to terminal C. The stick circuit for relay SR2 now passes from terminal B through front contact 36 of relay Q, front contact 16 of relay SR2 and the winding of relay SR2 to terminal C.

In describing the operation of the apparatus of Fig. 6, I shall first assume that the track sections D—E and E—F are unoccupied so that the apparatus is in its normal condition as shown in Fig. 6. In this condition of the apparatus, relays TR1 and TR2 are held energized over their respective holding circuits, relay TP3 is energized over its normal energizing circuit, relays SR1, SR2 and Q are deenergized, and signal S is deenergized. I shall now assume that an eastbound train enters section D—E with the result that relay TR1 is shunted and releases. The release of relay TR1 opens front contact 54, thereby opening the normal energizing circuit for relay TP3 so that relay TP3 releases to

close back contact 33 and set signal S into operation. Signal S now displays its warning indication to highway users of the approach of the train. The release of relay TR1 also closes back contacts 11, 31 and 34. The closing of contact 11 of relay TR1 completes the pick-up circuit for relay SR1 so that relay SR1 picks up to close front contact 14 and prepare the stick circuit for that relay, to close front contact 29 and prepare the first circuit in the pick-up circuit of relay TR2, and to close front contact 57 and prepare the third circuit for relay TP3. The back contacts 15 and 66 also open when relay SR1 picks up, to open, respectively, the pick-up circuit for relay SR2 and the second circuit in the pick-up circuit for relay TR2. The closing of back contact 64 of relay TR1 completes the circuit for relay Q so that relay Q picks up to close front contact 36 to complete the stick circuit for relay SR1, and to close front contact 42, thereby completing the first branch path in the pick-up circuit for relay TR1 whereby relay TR1 is connected across the track rails over its pick-up circuit. When the train enters track section E—F, relay TR2 releases to close back contacts 13, 32 and 65, the last contact completing its circuit for relay Q, and back contact 32 preparing the third energizing circuit for relay TP3.

When the train vacates section D—E, relay TR1 picks up to open back contacts 11, 31 and 64, and to close front contact 54. The opening of back contact 11 of relay TR1 opens the pick-up circuit for relay SR1, which relay is now energized over its stick circuit, and the opening of back contact 64 of relay TR1 opens the circuit for relay Q through that contact, relay Q now being held energized over back contact 65 of relay TR2. The closing of front contact 54 of relay TR1 completes the third energizing circuit for relay TP3 whereby relay TP3 picks up to open back contact 33 and terminate the operation of signal S. The picking up of relay TP3 also closes front contact 30 and thereby completes the first branch path in the pick-up circuit for relay TR2 so that relay TR2 is connected across the track rails over its pick-up circuit.

When the train vacates section E—F, relay TR2 picks up to close front contact 55 and thereby complete the normal circuit for relay TP3, and to open back contacts 32 and 65, which contacts open, respectively, the third circuit for relay TP3 and the circuit for relay Q. Relay Q releases at the end of the slow release period to open front contact 36 and thereby open the stick circuit for relay SR1, and to open front contacts 42 and 43, the opening of front contact 42 opening the pick-up circuit for relay TR1 so that relay TR1 is held energized over its holding circuit. Relay SR1 releases at the end of its slow release period, thereby opening front contact 29 to open the pick-up circuit for relay TR2 and thereby connect relay TR2 across the track rails over its holding circuit. The apparatus is now restored to its normal condition.

The operation of the apparatus of Fig. 6 for a westbound train is similar to that just described for an eastbound train, as will readily become apparent from an inspection of Fig. 6.

It should be pointed out that the directional control is maintained by virtue of the slow pick-up feature of the operating relay TP3 and the slow releasing feature of the directional stick relay SR1 or SR2, which relays cooperate with the auxiliary relay Q in governing the pick-up

circuits for relays TR1 and TR2. Thus, the directional control is not affected by a loss of train shunt in section D—E while the train is entirely within section D—E, since relay Q will release 5 when the track relay TR1 picks up because of the loss of train shunt, and relay Q upon releasing will transfer relay TR1 to its holding circuit so that the track relay is more likely to release again prior to relay SR1 or SR2 releasing. The slow acting features of the relay TP3 and relay SR1 or SR2 cooperate in a similar manner to maintain the directional control in the event that a loss of train shunt occurs in section E—F while the train is entirely within 10 section E—F. In either case, the slow pick-up feature of relay TP3 maintains signal S operating until the track relay TR1 or TR2 releases.

In Fig. 7, an auxiliary relay L, which is energized in series with relay SR1 or SR2, 15 cooperates with the stick relays to govern the release sensitivity of the track relays. Referring to Fig. 7, the pick-up and stick circuits for the directional stick relays SR1 and SR2 are the same as traced in connection with Fig. 3 except 20 that the winding of relay L is interposed in the connection of relays SR1 and SR2 and battery terminal C. The lower terminals of coils 6 and 8 of relay TR1 are connected at times over a first circuit serially including front contact 34 of relay 25 L and back contact 68 of relay SR2, and at other times connected over a second circuit serially including front contact 70 of relay TR2 and front contact 71 of relay SR2. The lower terminals of coils 6a and 8a of relay TR2 are at times 30 connected over a first circuit serially including front contact 35 of relay L and back contact 69 of relay SR1, and at other times connected over a second circuit serially including front contact 35 of relay L and front contact 73 of relay SR1. 35 The first energizing circuit for signal S passes from terminal B through back contact 58 of relay SR2, back contact 59 of relay TR1 and the winding of signal S to terminal C, and the second circuit for signal S passes from terminal B through back contact 60 of relay SR1, back contact 61 of relay 40 TR2 and the winding of signal S to terminal C.

When the track sections D—E and E—F are unoccupied, the apparatus is in its normal condition as shown in Fig. 7. The entrance of an 45 eastbound train upon track section D—E deenergizes relay TR1, and relay TR1 releases to close back contact 59 and thereby complete the first operating circuit for signal S so that signal S starts operating. Back contact 11 of relay TR1 also closes to complete the pick-up circuit for relays SR1 and L, the relays SR1 and L picking up. When relay L picks up, front contact 34 of relay L closes to connect relay TR1 across the track rails in its pick-up circuit. 50 When relay SR1 picks up back contacts 15, 60 and 69 of relay SR1 open, and front contacts 14 and 13 of relay SR1 close. When the train enters track section E—F, relay TR2 becomes deenergized, and back contact 13 of relay TR2 closes to complete the stick circuit for relays SR1 and L. The reenergization of relay TR1, when 55 the train vacates track section D—E, opens back contact 59 to open the first operating circuit for signal S whereby the operation of signal S is terminated, and back contact 11 of relay TR1 opens to open the pick-up circuit for relay SR1. Front contact 72 of relay TR2 also closes to connect relay TR2 across the track rails in its pick-up circuit. When the train vacates track section 60 E—F, relay TR2 is reenergized, relays SR1

and L are deenergized, relays TR1 and TR2 are again connected across the track rails in their respective holding circuits, and the apparatus is restored to its normal condition.

The operation of the apparatus of Fig. 7 for a westbound train is similar to that just described for an eastbound train, as will readily become apparent from an inspection of Fig. 7.

In this form of my invention, directional control is maintained by virtue of the slow release characters of the stick relays SR1 and SR2, and although the operation of the signal may be interrupted when a loss of train shunt occurs in track section D—E, the slow release characteristics of the stick relay SR1 prevents the loss of directional control, as was explained in detail in the operation of the apparatus of Fig. 3.

It should be noted that relay L is only slightly slow releasing and is controlled by track relay TR1 in a manner such that a momentary loss of the train shunt, while relay TR1 or TR2 is connected across the track rails in its pick-up circuit, results in the release of relay L when the track relay picks up. The release of relay L immediately transfers that track relay, energized over its pick-up circuit, to its holding circuit, so that ordinarily the track relay will again become released before a change will be effected in the control of the directional stick relay SR1 or SR2.

Referring now to Fig. 8, the apparatus is the same as described for Fig. 7 except that the lower terminals of coils 6 and 8 of relay TR1 are at times connected over a circuit including front contact 34 of relay L, the lower terminals of coils 6a and 8a of relay TR2 are at times connected over a circuit including front contact 35 of relay L, and relays TR1 and TR2 are each provided with a shunt path across the operating winding of the relays.

The shunt path provided around the winding of relay TR1 passes from the right-hand terminal of relay TR1 through front contact 71 of relay SR2 and back contact 76 of relay TR2 to the left-hand terminal of relay TR1. Similarly, the shunt path provided around the winding of relay TR2 passes from the right-hand terminal of relay TR2 through front contact 79 of relay SR1 and back contact 78 of relay TR1 to the left-hand terminal of relay TR2.

When the track sections D—E and E—F are unoccupied, the apparatus is in its normal condition as shown in Fig. 8. In this condition of the apparatus, relays TR1 and TR2 are energized, and signal S and relays SR1, SR2 and L are deenergized. The entrance of an eastbound train on section D—E deenergizes relay TR1 so that back contact 59 of relay TR1 closes to complete the operating circuit for signal S, and signal S starts operating. Back contact 11 of relay TR1 also closes to complete the pick-up circuit for relay SR1 so that relay SR1 becomes energized to open back contacts 15 and 60, and to close front contacts 14 and 79. Since back contact 78 of relay TR1 closed when relay TR1 released, the closing of front contact 79 of relay SR1 completes the shunt path around the winding of relay TR2, and relay TR2 releases to close back contacts 13, 61 and 76. Relay L, energized in series with relays SR1 and SR2, is now picked up so that relay TR1 is connected across the track rails in its pick-up circuit, and the full operating winding of relay TR2 is shunted by the shunt path previously traced for the winding of relay TR2.

When the train enters section E—F, the ap-

paratus remains in the condition just described since relay TR2 is deenergized by virtue of the preliminary shunt path governed jointly by relays TR1 and SR1. When the train vacates section 5 D—E, relay TR1 becomes reenergized to open the circuit for signal S with the result that signal S no longer operates, and to open the shunt path around the winding of relay TR2. Relay TR2 is now retained deenergized by virtue of the train 10 shunt in section E—F. When the train vacates the section E—F, relay TR2 becomes reenergized to open back contacts 13, 61 and 76, relays SR1 and L become deenergized, relays TR1 and TR2 are again connected across the track rails in 15 their respective holding circuits, and the apparatus is restored to its normal condition.

When the train is within section D—E, a momentary high resistance train shunt will not affect the directional control for signal S. That 20 is to say, relay TR1 might pick up due to the high resistance train shunt and thereby interrupt the operation of signal S at front contact 59. However, the picking up of relay TR1 opens the shunt path around relay TR2 with the result 25 that relay TR2 picks up. With relays TR1 and TR2 picked up, the pick-up and stick circuits for relays SR1 and L are opened, with the result that relay L releases to transfer relays TR1 and TR2 to their respective holding circuits and so 30 reduce the energization of the relays so that ordinarily relay TR1 will again release to restore the pick-up circuit for relay SR1 prior to relay SR1 releasing. It can be seen, therefore, that a momentary loss of train shunt does not affect 35 the directional control of the signal S. In like manner, when the train has vacated section D—E and is entirely within section E—F, the momentary high resistance train shunt will not affect the direction control of signal S and effect im- 40 proper signal operation. Relay TR2 might pick up due to the high resistance train shunt, and thereby open the stick circuit for relays SR1 and L, but relay L will release and transfer relay TR2 to its holding circuit and thus reduce the energization of relay TR2 so that relay TR2 releases 45 prior to relay SR1 releasing.

It is obvious that the operation of the apparatus of Fig. 8 for a westbound train is similar to the operation just described for an eastbound 50 train, as will readily become apparent from an inspection of Fig. 8.

In Fig. 9, a single auxiliary relay L1 is associated with both windings of an interlocking relay to provide a primary-secondary relay combination. Referring to Fig. 9, winding W3 of an interlocking relay IR1 is illustrated in the form 55 of two coils 6b and 8b having a resistor 9b permanently connected across an intermediate terminal of coil 6b and the lower terminal of coil 8b. The upper terminals of coil 6b of winding W3 are connected with rail 1 of section D—E, and the upper terminal of coil 8b is connected with rail 1a of section D—E, battery 3 being connected across the track rails 1 and 1a of section D—E 60 to thereby establish a track circuit. The lower terminals of coils 6b and 8b of winding W3 are at times connected together over a circuit including front contact 46 of the relay L1, to be referred to later. The track circuit for section 65 E—F is similarly provided by connecting battery 3 across the track rails 1 and 1a of section E—F, the upper terminal of coil 6c being connected with rail 1, the upper terminal of coil 8c being connected with rail 1a, the lower terminals of 70 coils 6c and 8c of winding W4 being connected 75

at times together over a circuit including front contact 45 of relay L1, and resistor 9c being permanently connected across an intermediate terminal of coil 6c and the lower terminal of coil 8c. It can be seen that when the lower terminals 5 of coils 6b and 8b of winding W3, or of coils 6c and 8c of winding W4, are connected together, winding W3 or winding W4 is then connected 10 in its pick-up circuit whereby the energy level of the winding is relatively high since the full operating winding is energized. However, when the lower terminals of the relay coils are disconnected from each other and the windings are connected 15 in their holding circuits, the energy level of the windings is greatly reduced.

The interlocking relay IR1 may be of the same type as described in connection with Fig. 1. It should be noted, however, that winding W3 is provided with two back contacts 50 and 52 closed only in the full release position of the winding, is provided with back contact 48 closed both in the full released and the "locked up" position of the winding, and is provided with a front "flagman" contact 46 which is open only in the full released position of the winding. Similarly, winding W4 20 is provided with the two back contacts 51 and 53 closed only in the full released position of the winding, is provided with back contact 49 closed both in the full released and "locked up" position 25 of the winding, and is provided with front "flagman" contact 47 open only in the full released position of the winding.

Relay L1, referred to previously, is provided with an energizing circuit passing from terminal B through back contact 48 of winding W3 or 35 back contact 49 of winding W4 and the winding of relay L1 to terminal C. Relay L1 is preferably provided with slightly slow releasing characteristics.

Signal S is provided with an operating circuit 40 passing from terminal B through back contact 52 of winding W3 or back contact 53 of winding W4 and the winding of signal S to terminal C.

A shunt path is provided around coils 6b and 8b of winding W3, the path passing from the 45 left terminal of winding W3 through front "flagman" contact 46 of winding W3 and back contact 51 of winding W4 to the right terminal of relay W3. Similarly, a shunt path is provided around coils 6c and 8c of winding W4, the path passing 50 from the left terminal of winding W4 through back contact 50 of winding W3 and front "flagman" contact 47 of winding W4 to the right terminal of winding W4.

The apparatus of Fig. 9 assumes its normal 55 condition when no train is within track section D—E or E—F. In this condition, windings W3 and W4 are held energized over their respective holding circuits, signal S does not operate, and relay L1 is deenergized. When an eastbound 60 train enters section D—E, winding W3 releases to close back contact 52 and complete the operating circuit for signal S so that signal S starts operating. The release of winding W3 also closes back contact 48 to complete the energizing circuit 65 for relay L1, relay L1 thereby picking up to close front contacts 44 and 45, which contacts complete the pick-up circuits for windings W3 and W4, respectively. Back contact 50 of winding W3 also closes to complete the shunt path around 70 the winding W4 with the result that winding W4 releases. Front contact 47 of winding W4 is now held closed and back contacts 51 and 53 are held open by the interlocking feature of relay IR1, and back contact 49 of winding W4 closes. 75

This shunting of the second winding W4 of relay IR1, forcing that winding into a locked position, assures directional control prior to the entrance of a train upon track section E—F and also prevents the loss of directional control. As winding W4 is already in a deenergized condition, the entrance of the train on track section E—F has no effect upon the operation of the apparatus. However, if the train shunt in section D—E becomes lost just prior to the train entering section E—F, the shunt around winding W4 aids in maintaining the directional control. That is to say, directional control of the signal operation can be lost only if winding W3 becomes picked up to remove the shunt around winding W4, and winding W4 is picked up and then released prior to the train shunt being restored to section D—E so that winding W3 is released. And since winding W4 cannot become energized until winding W3 becomes picked up, this delay ordinarily will permit the train shunt to be restored to section D—E and winding W3 releasing prior to winding W4 picking up and releasing. Thus the shunting of winding W4 when winding W3 releases in effect makes winding W4 slow acting.

When the train vacates section D—E, winding W3 picks up to open back contact 52, thereby terminating the operation of signal S. The picking up of winding W3 also opens back contacts 48 and 50. When back contact 50 opens, the shunt path around winding W4 is removed, but winding W4 is held released by virtue of the train shunt in section E—F. The opening of back contact 48 of winding W3 interrupts the energizing circuit for relay L1 governed by that contact, but relay L1 is retained energized by virtue of its circuit including back contact 49 of winding W4.

When the train vacates track section E—F, winding W4 picks up and relay L1 releases to connect windings W3 and W4 across the track rails in their holding circuits.

The operation of the apparatus for a westbound train is similar to the operation of the apparatus just described for an eastbound train, as will readily become apparent from an inspection of Fig. 9.

One advantage of apparatus embodying my invention is the provision of means to combine track circuits sensitive to train shunting with directional control apparatus to obtain traffic controlling signal control apparatus remarkably free from false operation. This freedom from false operation, or loss of direction control, is obtained by means of simple and reliable apparatus and provides a most desirable control for highway traffic controlling signals.

Although I have herein shown and described only a few forms of railway signaling apparatus embodying my invention, it is understood that various changes and modifications may be made therein within the scope of the appended claims without departing from the spirit and scope of my invention.

Having thus described my invention, what I claim is:

1. In combination with a stretch of railway track divided into two track sections, a signal, a first track relay operatively associated with one of said sections, a second track relay operatively associated with the other of said sections, a first slow releasing stick relay associated with the first track relay for controlling said signal during traffic movements in one direction, a second slow releasing stick relay associated

with the second track relay for controlling said signal during traffic movements in the opposite direction, a pick-up circuit for each stick relay including a back contact of the associated track relay and a back contact of the other stick relay, a stick circuit for each stick relay including a front contact of the stick relay and a back contact of the other track relay, an auxiliary relay controlled by both of said track relays, and circuit means controlled jointly by said auxiliary relay and by each track relay for at times controlling the release sensitivity of that track relay. 5

2. In combination, a stretch of railway track over which traffic moves in both directions and intersected by a highway, said stretch being divided into two track sections extending in opposite directions from the intersection and each section being provided with a track circuit including a track relay, a highway crossing signal located at the intersection, operating means governed by each track relay for operating the signal when a train approaches the intersection, directional means including slow releasing stick relays controlled by said track relays for preventing the operation of the signal when a train 20 recedes from the intersection through a track section, an auxiliary relay controlled by both of said track relays, and circuit means controlled jointly by said auxiliary relay and by each track relay effective at times to cut out a portion of the 25 operating winding of that relay to thereby control the release sensitivity of that relay. 30

3. In combination, a stretch of railway track over which traffic moves in either direction and intersected by a highway, said stretch being divided into two track sections extending in opposite directions from the highway and each section being provided with a track circuit including a track relay, a highway crossing signal located at the intersection, operating means governed 35 by each track relay for operating the signal when the train approaches the intersection, two directional stick relays controlled by the track relays for preventing the operating means from operating the signal when a train moves through a track section in receding from the intersection, an auxiliary relay controlled by both of the track relays, and means governed by said auxiliary relay which at times provides a path around a portion of the operating winding of each track 40 relay for controlling the release sensitivity of the track relays. 45

4. In combination, a stretch of railway track divided into a first and a second track section and intersected by a highway at substantially the junction of said sections, a highway crossing signal located at such intersection, a track circuit for said first track section including a first track relay, a track circuit for said second section including a second track relay, a stick relay associated with each track relay, a pick-up circuit for each stick relay including a back contact of the other stick relay and a back contact of the associated track relay, a stick circuit for each stick relay including a back contact of the other track relay, an operating relay, circuit means governed jointly by said track relays and said stick relays for energizing said operating relay at all times except when either one of said two track sections is occupied by a train approaching the intersection, operating means including a back contact of said operating relay for operating the signal, and circuit means governed jointly by said operating relay and said stick relays for at times reducing the effective 50 55 60 65 70 75

number of coil turns of the track relays included in their associated track circuits.

5. In combination, a stretch of railway track divided into a first and a second track section and intersected by a highway at substantially the junction of said sections, a highway crossing signal located at such intersection, a track circuit for said first section including a portion of the operating winding of a first track relay, a track circuit for said second section including a portion of the operating winding of a second track relay, a slow releasing stick relay associated with each track relay, a pick-up circuit for each stick relay including a back contact of the associated track relay and a back contact of the other stick relay, a stick circuit for each stick relay governed by a back contact of the other track relay, an operating relay, circuit means controlled jointly by said track relays and said stick relays effective for energizing said operating relay at all times except when either one of said two track sections is occupied by a train approaching the intersection, operating means including a back contact of said operating relay for operating the signal, an auxiliary relay controlled by back contacts of said track relays, and other circuit means governed jointly by said operating relay and said auxiliary relay effective at times for interposing the full operating winding of at least one of said track relays in its track circuit.

6. In combination, a stretch of railway track over which traffic moves in either direction and intersected by a highway, said stretch being divided into two track sections extending in opposite directions from the intersection and each track section being provided with a track circuit including a track relay, a highway crossing signal located at the intersection, a slow releasing stick relay associated with each track relay, a pick-up circuit for each stick relay including a back contact of the associated track relay and a back contact of the other stick relay, a stick circuit for each stick relay including a back contact of the other track relay, an operating circuit governed by each track relay and including a back contact of the other stick relay for operating said signal when a train approaches the intersection, an auxiliary relay controlled by both said track relays, and means governed by said auxiliary relay effective at times to cut out a portion of the operating winding of at least one of said track relays included in its associated track circuit.

7. In combination, a stretch of railway track over which traffic moves in both directions and which is intersected by a highway, said stretch being divided into two track sections extending in opposite directions from the intersection and each track section being provided with a track circuit including a track relay, a highway crossing signal located at the intersection, a slow releasing stick relay associated with each track relay, a pick-up circuit for each stick relay including a back contact of the associated track relay and a back contact of the other stick relay, a stick circuit for each stick relay including a back contact of the other track relay, circuit means for operating the signal when a train approaches the highway including a back contact of each track relay and a back contact of the other stick relay, an auxiliary relay controlled by each of said track relays, and means governed jointly by said auxiliary relay and said stick relays for at times excluding a portion of the

operating winding of each track relay from its associated track circuit.

8. In combination, a stretch of railway track divided into a first and a second track section and intersected by a highway substantially at the junction of said sections, a highway crossing signal located at such intersection, a track circuit for each track section including a track relay, a slow releasing stick relay associated with each track relay, a pick-up circuit for each stick relay including a back contact of the associated track relay and a back contact of the other stick relay, a stick circuit for each stick relay including a back contact of the other track relay, an operating circuit governed by each track relay and including a back contact of the other stick relay for operating said signal when a train approaches the intersection, an auxiliary relay controlled by each of said track relays, and means governed by said auxiliary relay for at times controlling the release sensitivity of each track relay.

9. In combination, a stretch of railway track divided into two adjoining track sections and intersected by a highway at substantially the junction of said sections, a highway crossing signal located adjacent such intersection, two track relays one for each of said sections, two track circuits one for each of said two sections and each normally effective to create in the associated track relay a first energy level which is sufficient to maintain that relay picked up, two slow releasing stick relays one for each of said two track relays, a pick-up circuit for each stick relay including a back contact of the other stick relay and controlled by a back contact of the associated track relay, a stick circuit for each stick relay controlled by a back contact of the other track relay, an operating relay, circuit means controlled jointly by said track relays and by said stick relays for energizing said operating relay at all times except when either one of said two sections is occupied by a train approaching the intersection, circuit means controlled by said operating relay for operating said signal, and circuit means controlled by each track relay and effective upon the release of a track relay for conditioning that relay to create a second energy level which is sufficient to pick up that relay.

10. In combination, a stretch of railway track divided into two adjoining track sections and intersected by a highway at substantially the junction of said sections, a highway crossing signal located adjacent such intersection, two track relays one for each of said sections, two track circuits one for each of said two sections and each normally effective to create in the associated track relay a first energy level which is sufficient to maintain that relay picked up, two slow releasing stick relays one for each of said two track relays, a pick-up circuit for each stick relay including a back contact of the other stick relay and controlled by a back contact of the associated track relay, a stick circuit for each relay controlled by a back contact of the other track relay, an operating relay, circuit means controlled jointly by said track relays and by said stick relays for energizing said operating relay at all times except when either one of said two sections is occupied by a train approaching the intersection, circuit means controlled by said operating relay for operating said signal, and circuit means controlled jointly by said operating relay and by said stick relays for selectively conditioning each of said two track relays to create a second energy level which is sufficient to pick up that relay,

whereby the track relay located in approach of the intersection is conditioned to be picked up as long as such relay is released and the track relay located in advance of the intersection is conditioned to be picked up whenever such latter relay is released provided that the approach track relay then is picked up.

11. In combination, a stretch of railway track divided into two adjoining track sections and intersected by a highway at substantially the junction of said sections, a highway crossing signal located adjacent such intersection, two track relays one for each of said sections, two track circuits one for each of said two sections and each normally effective to create in the associated track relay a first energy level which is sufficient to maintain that relay picked up, two slow releasing stick relays one for each of said two track relays, a pick-up circuit for each stick re-

lay including a back contact of the other stick relay and controlled by a back contact of the associated track relay, a stick circuit for each stick relay controlled by a back contact of the other track relay, an operating relay, circuit means controlled jointly by said track relays and by said stick relays for energizing said operating relay at all times except when either one of said two sections is occupied by a train approaching the intersection, circuit means controlled by said operating relay for operating said signal, an auxiliary relay controlled by both of said two track relays, and circuit means controlled jointly by said operating relay and by said auxiliary relay and by said stick relays for selectively conditioning each of said two track relays to create a second energy level which is sufficient to pick up that relay. 5 10 15

PAUL N. MARTIN.
